CLAIM

The ornamental design for a photo booth, as shown and described.

DESCRIPTION

FIG. 1 is a perspective view of a photo booth showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged portion view taken from encircled portion labeled, “FIG. 9,” in FIG. 1.

The dashed-dot lines form the boundary of the enlarged portion view of FIG. 9 in FIGS. 1 and 9 and form no part of the claimed design. The even dashed broken lines shown in

(Continued)

the drawings are included for the purpose of illustrating portions of the photo booth that form no part of the claimed design.

1 Claim, 9 Drawing Sheets
